ELECTRIC BLOOD PRESSURE DIAGNOSTIC
DEVICEWalter J. Loria, New York, and Jerome Suhre,
Richmond, N. Y.

Application April 7, 1945, Serial No. 587,136

11 Claims. (Cl. 128—2.05)

1

This invention generally relates to devices adapted to indicate specified characteristics of the flow of a fluid through a conduit and is more particularly concerned with an electronic device of this nature which will indicate the nature, volume, change in volume or the pulsating flow or any combination of these, of a fluid through a flexible conduit, for example, for medical diagnosis.

In the diagnosis and treatment of a great variety of diseases of humans, and also in routine health examinations thereof, the arterial blood pressure of the patient is of vital interest to the examining physician or like technician, and also the rate of pulse beat often is desired.

The arterial pressure in the larger arteries of the patient shows marked variations with the heart beat, the pressure during the beat of the heart, known as systolic pressure, being of a much higher level than the diastolic pressure.

Heretofore, it has been usual for the examining physician to utilize for the identification of the arterial blood pressure of a patient, the application of pressure upon an artery (for example, the brachial artery), by surrounding a limb of the patient with a pressure bag which can be inflated by air pressure to a measured amount and thereafter the pressure is slowly released by a bleed valve, for example, during which time the physician notes through his stethoscope, the changes in flow of blood through the artery as it commences to flow again after it has been cut off by the tourniquet effect of the pressure bag. By visually noting the pressures as registered for instance on a manometer, at specified points defined by his aural reactions through the stethoscope, the physician is able to identify the specific systolic and diastolic pressures for the patient under examination. Such a device is known as a sphygmomanometer.

It is recognized that such a device, while generally satisfactory, depends much upon the individual skill of the examining physician and also has many obvious disadvantages including the use of cumbersome equipment, the necessity for the physician's hands to be fully occupied in the obtaining of results, and non-sensitivity of the pressure indicating means.

Furthermore, such a device as heretofore used, does not permit the indicating of pulse rate, and

2

to take this, the physician must independently use tactual impression to time the rate of pulse beat.

It is also known to utilize a similar device to a sphygmomanometer for diagnostic purposes in which the pressure indication means is replaced by a mechanical indicating means, whereby the relative blood pressures in different parts of the body of a patient may be obtained for comparison.

10 This device is usually known as a medical oscilloscope, and again the device is non-sensitive, relatively inaccurate, and only generally satisfactory.

It is, accordingly, the general object of the present invention to improve over existing devices 15 for medical diagnosis relating to conditions of blood pressure in the human system and provide a device, adaptable for the purposes above indicated, as well as for equivalent purposes, which is sensitive, accurate, simple to operate, easy to read, and can be manipulated by the examining technician with greater freedom.

More specifically, the present invention provides a sphygmomanometer which is extremely and accurately sensitive to the changes of arterial 20 blood pressure and which is simple in operation.

A further object of the invention is to provide an oscilloscope which is more sensitive, accurate and easy to utilize than the oscilloscopes heretofore used.

30 Furthermore, the invention provides means for visually indicating the pulse rate of a patient without tactile operation by the examining technician.

Objects and advantages of the invention will 35 be set forth in part hereinafter and in part will be obvious herefrom, or may be learned by practice with the invention, the same being realized and attained by means of the instrumentalities and combinations pointed out in the appended 40 claims.

The invention consists in the novel parts, constructions, arrangements, combinations and improvements herein shown and described.

According to the invention there is provided a 45 light-sensitive means which is rendered operative to indicate changes in pressure when the usual pressure bag heretofore described is slowly deflated by a bleed valve or the like, such changes being translated by electronic means to simultaneously indicate the pressure applied by the

pressure bag at all times, and the pulse amplitude of the patient. When the device is used as an oscilloscope, these are the desired readings, since the pressure bag is placed on various parts of the human body and the amplitudes at these various parts are compared for diagnosis.

In the use of the device as sphygmomanometer, the blood pressure reading is given as first systolic and then diastolic in the conventional and desired order.

Preferably, in each use of the device given above, the pulse rate is simultaneously indicated on a separate indicator such as a suitable meter.

In carrying out the invention, there is provided a first suitable source of constant illumination which is adapted to impinge upon a first photoelectric tube, the amount of light transmitted being varied, and following the indications of a first aneroid capsule which is directly influenced through a flexible conduit by the air pressure exerted on the patient by virtue of the conventional pressure bag which is wrapped around the patient's arm, leg or the like and inflated by suitable means such as a conventional bulb. Thus the pressure applied may be recorded on a suitable meter through an amplifying electronic circuit from the first photoelectric tube and as the pressure is released, utilizing for example a bleed valve on the inflating bulb or the flexible conduit which is connected with the bladder or like inflatable part of the pressure bag. Any desired amplification of the electric current caused to flow from the photoelectric tube by virtue of the light variations impinging thereon, may be employed to give a desired sensitivity and, if desired, two or three scale readings may be obtained on the meter by shunts or the like, operable to give varied ranges of indicated pressure, as well as accurate readings. The variations of light may be suitably obtained by an opaque shield on the moving vane mounted to move with the vane of the aneroid capsule past a fixed aperture and weighted or damped to avoid oscillations due to varied pressures.

The recording of pulse amplitude is obtained by mounting a second apertured shield, to the moving vane of the aneroid capsule, aforesaid, and by mounting it to move past its own fixed aperture and parallel with the moving vane of the second aneroid capsule, upon which is mounted a single opaque shield and undamped, so that light will pass through the opening of the apertured shield and fixed aperture in constant quantities at all times, unless interrupted by the movement of the second undamped shield, which readily responds to the fluctuations of pulse amplitudes which will commence when the applied pressure of the pressure bag has become reduced enough to permit flow of blood through the artery, thus in effect opening and closing the aperture to a degree proportional to the pulse amplitude thereby permitting light to pass through the aperture, in direct proportion to the pulse amplitude.

A second source of illumination coacts with a second photoelectric tube through the second apertured shield and fixed aperture whereby the fluctuations of the blood pressure may be indicated on a second suitable meter, such as an ammeter, electronic amplification being utilized to obtain a sensitive reading thereon.

When used as an oscilloscope, the indication read upon the second meter will be comparable with readings taken with respect to other parts

of the body, and the relative amplitude on the first meter will be noted for such readings.

When used as a sphygmomanometer the reading on the second meter will be first a small indication on the dial showing the systolic beat at which time the pressure on the first meter will be noted, and thereafter a much larger indication on the second meter will show the diastolic beat at which time the pressure on the first meter will again be taken, this specific change of indication on the first meter being equivalent to the aural change noted by the physician when using a stethoscope.

When it is desired to incorporate a pulse rate indicator into this device, an additional electronic amplifying circuit is cut into the circuit controlled by the second photoelectric tube and is operated therefrom through a relay to give unidirectional surges of pressure during the systolic and diastolic indications on the second meter, whereby by suitable calibration, the direct pulse rate may be shown on a third meter such as an ammeter controlled by the relay. Preferably, the operating current to the third meter is damped, as by a resistance-capacitor coupling, to give a nonfluctuating reading thereon.

Obviously, the second and third meters mentioned may have two or more scales with suitable means to permit reading on a desired scale, as defined with respect to the first meter.

The circuit with respect to the second meter, indicating the changes in flow, may be of variable sensitivity as by a potentiometer control on an amplifying tube whereby the physician may select a desired sensitivity easily and readily to assist his specific diagnosis.

It will be readily seen that the device herein provided has many advantages over prior devices for the same purpose, and that the device is not only more accurate, sensitive and easy to use, but also it readily forms an easy to read, compact instrument.

Furthermore, in practice, the reading on the second meter will vary only with the amplitude of the pulse beat and not with the applied pressure, and the reading on the first meter will be controlled only by the applied pressure and will not respond to the pulse beat. There is thus provided an instrument which indicates the instantaneous value of the applied pressure which acts simultaneously with the pulse amplitude, thereby enabling the physician to measure systolic pressure which is the pressure at which the pulse first appears on the second meter and the diastolic pressure which is the pressure at which the pulse amplitude is at its peak on the second meter, whereby to provide the physician with an instrument which may be used with comparative precision to ascertain the blood pressure in the arteries of man.

The accompanying drawings, referred to herein and constituting a part hereof, illustrate embodiments of the invention, and together with the description, serve to explain the principles of the invention.

Figure 1 is a plan view of one embodiment of the device according to the present invention;

Figure 2 is a side elevation, with certain parts in section, on the line 2-2 of Figure 1;

Figure 3 is a section on the line 3-3 of Figure 1;

Figure 4 is a section on the line 4-4 of Figure 3;

Figure 5 is a plan view of a detail of Figure 1

comprising the light intercepting vanes for the light sensitive means; and

Figure 6 is a diagrammatic wiring diagram of the electric elements used in the apparatus of Figure 1.

Referring now to the drawings, the elements comprising our instrument may be arranged in the portable casing 10. Secured in one wall 12 thereof there is provided a conventional electric current meter or ammeter 14 which is calibrated to indicate pressure, a second electric current meter or ammeter 16 which visually indicates fluctuations and pulse amplitude and which may be calibrated in units corresponding to pressure in centimeters of water or simply in units of arbitrary value, and a third electric current meter or ammeter 18 which is calibrated to indicate pulse rate in beats per second, these meters being hereinafter defined as to their functions. Thus, meter 14 may be termed an applied pressure indicator and meter 16 a pressure pulsation indicator.

Secured to the side wall 12 as by means of the brackets 20 and 22, there is provided a high frequency generator 38, to be hereinafter described, adapted to energize light sources in the form of light bulbs 24 and 30. Bulb 24 has a condensing lens 25 adapted to converge light on photoelectric tube 27 which is of a conventional type, lens 25 being mounted in a housing 26.

As will be described, the light from bulb 24 directed on the photoelectric tube 27 is varied with the fluctuations of pressure of the blood of that portion of the body to which the instrument is applied, and so generates electric impulses which rise and fall to visually indicate the presence of the pulse beat. The tube 27, as will be described, is connected through a suitably amplifying circuit to the meter 16 which therefore will indicate even the slightest changes in pulse amplitude and greatly magnify it.

Secured to the condensing lens housing 26 as by the bracket 28 is the second lamp 30 arranged in the shaded compartment 32, the light from lamp 30 being directed against a photoelectric tube 34, which, as will hereinafter be brought out, generates electric impulses which are proportional to the applied pressure. The photoelectric tube 34 is connected through a suitable circuit to the meter 14 to indicate pressure applied as by means of a pressure bag.

The light focused on the tube 34 is varied in direct proportion to the change in applied pressure so that the impulse generated by the tube 34 will be varied by a very slight change in applied pressure and said generated impulse can be greatly amplified, so that the meter 14 will disclose even a very minute change in pressure.

Suitably mounted within the casing 10 are a pair of aneroid capsules 40 and 42 which are connected to a flexible tube 44.

When the device is used either as a sphygmomanometer or an oscilloscope, this tube 44 is connected to the conventional inflation system utilized for such purposes, comprising a bulb, valve, bladder and cloth sleeve (all not shown).

To ascertain the blood pressure at the systole and diastole of the heart, the cloth sleeve, containing the bladder, is wound around a limb, for example the upper arm at the brachial artery, and the bladder inflated with air by means of the bulb to a level beyond the patient's systolic pressure, which is determined as described hereinafter. This air pressure is transmitted through the branch 46 into the first aneroid capsule 40 causing the vane 48 thereof to deflect, and

through the branch 50 into the second aneroid capsule 42 causing the vane 52 thereof to deflect.

Interposed between the vanes 52 and 48 and secured to a supporting bracket 54 affixed to the housing 10 by the set screws 56 is a stationary opaque curtain member 58 having a curvilinear aperture or opening 60 through which rays of light may be directed on to the photoelectric tube 27.

10 Vane 52 is provided with a shield 62 which is of such size that it will completely cover the opening 60 throughout its oscillatory radial travel about the center 63 (Figure 3) under the influence of air pressure in the aneroid capsule 42, from its normal or zero position to its fully deflected position, when the capsule 42 is under a predetermined maximum pressure.

The shield 62 is provided with an aperture 64 which permits the passage of light from the lamp 24 through the opening 60 onto the tube 27.

As the vane 52 moves under influence of pressure, at all positions reached by it in its travel, the window or opening 64 permits a constant quantity of light to pass through the opening 60 which is preferably curved to correspond to the path of travel of the shield 62.

Thus, when the light impinging on the tube 27 from lamp 24 is not intercepted, the meter 16 to which it is connected, as hereinafter described, 30 will indicate the presence of an electric current which does not vary by reason of any effect of the tube 27. When the air pressure of the pressure means is reduced however, and thus the pressure in conduits 46 and 50 is reduced, vane 48 and its appended opaque shield 65 will periodically intercept the light rays by, in effect, partially closing and opening the aperture 64 to a degree varying with the amplitude of the pulse beat at the systolic and diastolic pressure, and at blood pressures between systolic and diastolic and above and below systolic and diastolic, to produce corresponding variations in current flow through tube 27 and thereby indicate by such variations on meter 16, pulse amplitude at different values 45 of applied pressure.

In order to indicate concurrently the applied pressure, there is secured to the vane 52, a second shield 66 which intercepts light from the lamp 30 directed at the photoelectric tube 34. This tube 50 34 is connected to the meter 14 by means of an amplifying circuit, to be described hereinafter. To damp out the variations in blood pressure that would be imparted to the vane 52 in the same manner as they are imparted to vane 48 by the 55 pulse of the blood, a weight is applied to the end of vane 52 so that it will be too heavy to respond to the fluctuation of the pulse but will be deflected by applied pressure to assume the position that is dependent on and corresponds to the applied pressure.

As indicated in Fig. 3, normally, that is, in the absence of applied pressure, the shield 66 intercepts all of the light from the lamp 30 so that the photocell 34 is de-energized. As pressure is applied to the capsule 42, vane 52 rotates in a counterclockwise direction gradually to uncover photocell 34 and permit passage thereto of a beam of light of an area proportional to the applied pressure, so that readings on the meter 14 65 may be calibrated into pressure readings (such as mm. of mercury).

Since vane 48 is unweighted and comparatively light, it will respond not only to the applied pressure, namely it will move parallel to movements 70 of vane 52, but it will also fluctuate with the pulse

beats. The capsules 40 and 42 are initially adjusted so that, for any given mean positions of vanes 48 and 52, the shield 65 attached to the undamped vane 48 uncovers a minimum area of aperture 64 in shield 62 at the point in its cycle of oscillation at which the blood pressure is the lowest and uncovers a maximum area of aperture 64 at the point in the cycle at which the blood pressure is highest. Thus, the light that is directed on the tube 27 will vary from substantially zero when the window is covered, to a higher value when the window is uncovered.

Since the vane 52 is weighted to damp its oscillation, it will not follow the fluctuations of blood pressure but its position will vary with variations of the applied pressure over the range including the systolic and diastolic pressures. The vane 48 also assumes a mean position varying with applied pressure and thus its major movement follows that of vane 52. However, vane 48, being unweighted, oscillates about such mean position and the only variation in light reaching the photocell 27 is that due to oscillation of the shield 65 on vane 48 with respect to aperture 64 in shield 62 mounted on vane 52.

In Figure 6 is shown the wiring diagram with respect to the device. Photoelectric tube 27 is suitably connected to meter 16 through an amplifying circuit of conventional form comprising an amplifier pentode tube 68 and a triode amplifier tube 70. A voltage divider resistor 71 is utilized to couple the plate circuit of tube 68 to the grid of tube 70, the current meter 16 being connected in series in the plate circuit of tube 70 so as to respond to variations in the plate current thereof.

Photoelectric tube 34 is connected through a single triode amplifier tube 68' to its meter 14, which is connected in series in the plate circuit of tube 68' to respond to the plate current thereof, the required degree of amplification not being as great due to the meter 14 being of less sensitivity than meter 16 since it serves only to indicate relatively large increments of applied pressure, whereas meter 16 responds to relatively small applied increments of fluctuation.

The power supply 36 is in the form preferably of a voltage regulated supply of conventional form and the high frequency oscillator 38 is also of usual construction. Oscillator 38 is employed primarily to energize the lamps 24 and 30, since low frequency supply does not yield as constant and sensitive results.

In Figure 6, the circuit is also shown with respect to the energizing of the pulse rate meter 18. Where such indication is also desired incorporated in the one device, a relay 74 is incorporated in the circuit of meter 16, as shown, with its operating coil 72 actuated in synchronism with the fluctuations of energy supplied to meter 16. Meter 18 is connected to the high-frequency source 38 through the contacts of relay 74, a transformer 77, a diode rectifier 82, and a time constant of integrating circuit comprising a condenser 76 in parallel with the meter 18 and resistor 78 in series. The time constant of the circuit comprising elements 18, 76, and 78 is such that the average charge of the condenser 76 is proportional to the frequency of operation of the relay 74 and independent of the pulse amplitude utilized to actuate the relay 74. That is, the charge on condenser 76 is proportional to the pulse rate.

Thus, by means of the device of the present

invention the physician is enabled also to ascertain the pulse rate of the patient by a glance at meter 18, which accurately and quickly indicates changes in pulse rate. The coil 72 of a relay is arranged between one lead of the meter 16 and the plate of the tube 70, and as the tube current fluctuates, the armature 74 of the relay is opened and closed in synchronism with such fluctuations to cause flow of current in the coils of the transformer 77. There is thus induced or generated a current flow in the secondary coil of the transformer. This induced current is rectified by a rectifier tube 82 in the circuit of which the meter 18 is arranged. The pulsations of the rectified induced current are effective to charge condenser 76. Each pulse adds a substantially constant incremental charge to condenser 76 since the pulses are derived from a constant amplitude source 38. Between successive pulses, the charge of condenser 76 leaks off at a steady rate, depending on the voltage on the condenser. Thus, the condenser is charged to a voltage varying with the frequency of the pulse. The meter 18 is effectively energized by the voltage across condenser 76, the deflection of the needle of meter 18 corresponding in value with the charge of condenser 76. Thus by calibrating meter 18 in units corresponding to pulse velocity or rate, the physician is enabled to simultaneously observe the pulse rate at the same time that the meters 14 and 16 indicate applied pressure and blood pressure respectively.

In operation, the physician first inflates the sleeve or cuff above the patient's systolic pressure, which causes substantial stoppage of the flow of blood through the arteries. Nevertheless there will be a weak pulsation at the sleeve due to the pulsations of blood pressure from the heart which are transmitted weakly to the intake tube 44 of the apparatus due to the vane action of the blood in the portion of the limb above the sleeve in striking the sleeve. These weak pulsations cause a small amplitude oscillation of the undamped lightweight vane 48 and shield 65 operated by the aneroid capsule 40. The oscillation of the shield 65 causes the light falling on the photocell 27 from the lamp 24 to undergo low-amplitude pulsations. As shown in Fig. 6, pulsations of light on the photocell 27 results in amplified current pulsations in the plate circuits of the amplifier tubes 68 and 70 and these pulsations are indicated by the meter 16. At the same time, the high supersystolic pressure applied through the intake tube 44 to the aneroid capsule 42 causes a large deflection of its vane 52 and its connected shield 66 to a mean position proportional to the value of this supersystolic pressure. The deflection of the vane 52 causes the shield 66 to expose a substantial portion of the photocell 34 to light from the lamp 30 so that the illumination of the photocell results in an amplified current in the plate circuit of the tube 68' (Fig. 6) which includes the applied pressure meter 14. As explained above, the undamped vane 48 of the capsule 40 also assumes a mean position corresponding to that of the vane 52, since both the capsules 40 and 42 are exposed to the same mean pressure. However, due to the fact that the vane 48 is unweighted or undamped, it oscillates about this mean position, resulting in the amplified current oscillations supplied to the meter 16, as described, while the heavier or weighted vane 52 fails to follow these pulsations in pressure.

It will be understood that, while the meters 14 and 16 are conventional electric current meters or ammeters, they may be provided with scales

suitably calibrated to read directly in any convenient unit of pressure, for example, in millimeters of mercury, which is the conventional unit of the usual manometer.

The physician then slowly bleeds the pneumatic system by means of a bleed valve generally associated with the sleeve or cuff, allowing the pressure in the system to fall gradually. As the pressure in the sleeve falls, blood again begins to flow through the artery beneath the cuff and the amplitude of the pressure pulsations rapidly increases, causing an increase in the amplitude of the oscillation of the vane 48 and its associated shield 65 and a corresponding increase in the amplitude of oscillation of the meter 16 in the manner described above. Simultaneously, the mean pressure of the system, as indicated by the vane 52 of the capsule 42, its associated shield 68, photocell 34, amplifier 68', and meter 14, falls correspondingly. As is well known in diagnostics, there will be a point reached in the bleeding of the pneumatic system at which the amplitude of the pressure pulsations increases rapidly. This transition point is called the systolic pressure of the patient and, by the use of the apparatus of the invention, the physician may note on the meter 14 the mean pressure at which this rapid increase takes place and thus quickly obtain the value of a patient's systolic pressure.

As the bleeding of the pneumatic system progresses, the amplitude of the pressure pulsations continues to increase and, when these pulsations reach their maximum amplitude, as indicated on the meter 16, corresponding to the unrestricted flow of blood in the patient's arteries, the physician may note the pressure, termed the diastolic pressure, on the meter 14. Further bleeding of the pneumatic system causes both the amplitude of the pressure pulsations, as indicated on the meter 16, and the amplitude of the mean applied pressure, as indicated on the meter 14, to fall continuously, although the readings have less significance below the point at which the diastolic pressure is indicated.

Nevertheless, by the use of the system as described above, it is within the means of the physician to obtain continuous indications of the amplitude of the blood pressure pulsations as the mean blood pressure varies from a supersystolic value through the systolic value and on through the diastolic value to infra-diastolic values.

Simultaneously with the measurement of the blood pressure pulsations as described above, it will be noted that each pulse flowing in the plate circuit of the tube 70 (Fig. 6) and the meter 16 actuates the relay coil of the relay 74 causing it to close its contacts momentarily. Upon each closing of the contacts of the relay 74 the transformer 77 is energized from the source 38 and a series of pulses of high-frequency current of constant amplitude are transmitted through the transformer 77 and rectified by the rectifier tube 82 to charge the condenser 76. As explained above, the values of the condenser 76 and of the resistor 78 in parallel therewith are so selected in relation to the resistance of the meter 18 that, within the range of pulse frequencies generally encountered, the condenser 76 will receive an average rectified current through the relay 74 substantially equal to that which it discharges through the resistor 78 and the meter 18 in series during the interval between the series of pulses supplied by the relay 74. Under these conditions, a slight increase in the pulse rate causes the rectified pulses to be supplied to the condenser 76 more

frequently and the voltage across it will rise to the point at which again the average value of the discharge current through the meter 18 is substantially equal to the average value of the rectified current received. As stated above, the meter 18 responds to the value of the voltage across condenser 76 and, by the provision of a suitably calibrated scale, the meter 18 gives a direct indication of the pulse rate in pulses per minute. This provides the examining physician with additional diagnostic information useful in his examination of the patient.

Since the inflation of the cuff applies the pressure to the part under examination and the indicating meter 16 indicates the amplitude of the pulse or the volume of the blood in the arteries at the indicated pressure, it will be seen that comparison of the volume of blood in one limb with the volume of blood in the other limb, or the comparison of pulse amplitudes, may easily be accomplished by the physician by successively applying the inflatable bladder to such limbs. Thus, the physician is provided with an index to the condition of the circulating system of the limb under investigation and the corresponding limb or any other corresponding part of the extremities. The extreme sensitivity of the device according to the present invention provides the physician with a means of studying not only the major portions of the arms and legs, but also hands and fingers as well as the feet and toes, which, in the present state of the art, the physician is unable to accomplish because the usual form of sphygmomanometer is not sufficiently sensitive to investigate the feeble pulse in such extremities.

In the use of applicants' electric blood pressure diagnostic device, the physician is relieved of the use of the conventional stethoscope and sphygmomanometer.

While we have described in detail a modification of the present invention, and illustrated as embodied in a sphygmomanometer, or an electronic oscilloscope, it is to be understood that changes may occur to those skilled in this art but any permissible change must fall within the purview of the claims in this application.

The invention in its broader aspects is not limited to the specific mechanisms shown and described but departures may be made therefrom within the scope of the accompanying claims without departing from the principles of the invention and without sacrificing its chief advantages.

What is claimed is:

1. An electric blood-pressure diagnostic device for use with a pressure applying element and subject to blood-pressure pulsations comprising, an aneroid pressure capsule responsive primarily to pulsations of an applied pressure, a radiant energy source, a radiant energy responsive device disposed to be excited by said source for deriving an electrical effect varying with the excitation thereof, and means controlled by said pressure capsule for controlling the excitation of said device by said source, said electrical effect being representative of said applied pressure pulsations.

2. An electric blood-pressure diagnostic device for use with a pressure applying element and subject to blood-pressure pulsations comprising, an aneroid pressure capsule responsive primarily to pulsations of an applied pressure, a radiant energy source, a radiant energy responsive device disposed to be excited by said source for deriving an electrical effect varying with the excitation thereof, and a pivoted vane operated by said capsule

and interposed between said source and said device to control the excitation thereof, said electrical effect being representative of said applied pressure pulsations.

3. An electric blood-pressure diagnostic device for use with a pressure applying element and subject to blood-pressure pulsations comprising, means responsive primarily to pulsations of an applied pressure, a radiant energy source, a radiant energy responsive device disposed to be excited by said source for deriving an electrical effect varying with the excitation thereof, means controlled by said pressure responsive means for controlling the excitation of said device by said source, and a pressure pulsation indicator energized by said electrical effect.

4. An electric blood-pressure diagnostic device for use with a pressure applying element comprising, an applied pressure responsive means, means including an element controlled by said pressure responsive means responsive primarily to pulsations of an applied pressure, a radiant energy generating means, radiant energy responsive means disposed to be excited by said generating means for deriving electrical effects varying with the excitation thereof, and means controlled by said pressure responsive means for controlling the excitation of said energy responsive means by said generating means, means controlled by said pulsation responsive means for controlling the excitation of said energy responsive means by said generating means, said electrical effects being individually representative of said applied pressure and said applied pressure pulsations.

5. An electric blood-pressure diagnostic device for use with a pressure applying element comprising, an applied pressure responsive means, means including an element controlled by said pressure responsive means responsive primarily to pulsations of an applied pressure, a radiant energy generating means, a pair of radiant energy responsive devices disposed to be individually excited by said generating means for deriving electrical effects varying with the excitations thereof, means controlled by said pressure responsive means for controlling the excitation of one of said devices by said generating means, means controlled by said pulsation responsive means for controlling the excitation of the other of said devices by said generating means, an applied pressure indicator energized by the electrical effect derived by said one of said devices, and a pressure pulsation indicator energized by the other of said electrical effects.

6. An electric blood-pressure diagnostic device for use with a pressure applying element comprising, means responsive primarily to pulsations of an applied pressure, a radiant energy source, a radiant energy responsive device disposed to be excited by said source for deriving an electrical effect varying with the excitation thereof, means controlled by said pressure responsive means for controlling the excitation of said device by said source to derive a pulsating electrical effect, and means for integrating said pulsating electrical effect to derive an effect varying with the average frequency thereof, said last-named effect being representative of the pulse rate of the applied pressure.

7. An electric blood-pressure diagnostic device for use with a pressure applying element comprising, means responsive primarily to pulsations of an applied pressure, a radiant energy source, a radiant energy responsive device disposed to be excited by said source for deriving an electrical

75 effect varying with the excitation thereof, means controlled by said pressure responsive means for controlling the excitation of said device by said source to derive a pulsating electrical effect, relay means responsive to said pulsating electrical effect for deriving a secondary pulsating electrical effect of constant amplitude, and means for integrating said secondary pulsating electrical effect to derive an effect varying with the average frequency thereof, said last-named effect being representative of the pulse rate of the applied pressure.

8. An electric blood-pressure diagnostic device for use with a pressure applying element and subject to blood-pressure pulsations comprising, electrical means for developing an electrical effect, means responsive to applied pressure for controlling said electrical means to vary said electrical effect in accordance with variations in applied pressure, said pressure responsive means having the characteristic of being unresponsive to said blood-pressure pulsations, and an applied pressure representative device energized by said electrical effect.

9. An electric blood-pressure diagnostic device for use with a pressure applying element and subject to blood-pressure pulsations comprising, a radiant energy source, a radiant energy responsive device disposed to be excited by said source for deriving an electrical effect varying with the excitation thereof, means responsive to applied pressure for controlling the excitation of said device by said source to vary said electrical effect in accordance with variations in applied pressure, said pressure responsive means having the characteristic of being unresponsive to said blood-pressure pulsations, and an applied pressure representative device energized by said electrical effect.

10. An electric blood-pressure diagnostic device for use with a pressure applying element and subject to blood-pressure pulsations comprising, a radiant energy source, a radiant energy responsive device disposed to be excited by said source for deriving an electrical effect varying with the excitation thereof, means responsive to blood-pressure pulsations incident to applied pressure for controlling the excitation of said device by said source to vary said electrical effect in accordance with said blood-pressure pulsations, said pressure responsive means having the characteristic of being unresponsive to said applied pressure, and a pressure-pulsation representative device energized by said electrical effect.

11. An electric blood-pressure diagnostic device for use with a pressure applying element comprising two pressure responsive elements, each connected with a movable member and controlling its position, one of said movable members being formed with an aperture and damped so as to assume a mean position when subject to pulsations, a light source and a photocell on opposite sides of said damped member and arranged to provide a uniform beam through the aperture to the photocell in any position of the damped member, the other of said movable members being formed to screen said aperture in varying amounts subject to pulsing fluctuations in pressure above said mean, an electrical circuit including said photocell and an indicator for indicating the magnitude of such fluctuations, and means controlled by said damped member for indicating the magnitude of said mean pressure.
